Scavullo, Marie Scavullo Saegert, and Margaret
Scavullo Scott, all of Forest Hills, N. Y.

Continuation of application Serial No. 635,603,
December 17, 1945. This application October
12, 1950, Serial No. 189,813

2 Claims. (Cl. 29—148.2)

1

My invention relates to sheet metal hollow-ware articles, such as stainless steel hollow-ware articles and more particularly concerns a method of fabricating ornamented stainless steel and other sheet metal hollow-ware articles adapted for office, store, home, kitchen and for sundry generally allied applications; the present application for patent representing a continuation of my application Serial No. 635,603 of December 17, 1945, now abandoned.

Among the objects of my invention is the fabrication of ornamental sheet metal articles, particularly stainless steel articles of the general type described, and to impart to preformed hollow-ware articles an effective ornamental trim in a simple, ready, rapid, efficient and certain manner, which involves minimum investment of plant and equipment and labor, which can be effectively employed with metal sheets of widely divergent thicknesses and configuration, and which avoids all necessity of applied edging or molding.

Other objects and advantages in part will be obvious and in part pointed out hereinafter, during the course of the following more detailed description.

My invention accordingly resides in the features of construction and arrangement of parts, and in the several operational steps, and the relation of each of the same with one or more of the others, the scope of the application of all of which will be more fully set forth in the claims at the end of this specification.

In the drawings, wherein I disclose one embodiment of the apparatus which I now prefer for carrying my new method into operation, Figure 1 comprises a perspective view, and Figure 2 a front elevation of my new construction.

These views, wherein like reference numerals indicate like parts, effectively disclose the mode of application of my invention.

As conducive to a more ready understanding of the exact nature of my invention, it may be noted at this point that more and more stainless steel, as well as Monel metal, nickel, copper, brass, aluminum and like sheet metal, is used in the form of what may be termed ornamental hollow-ware. Particularly is this the case of stainless steel when advantage is to be taken of one or more of the many outstanding advantageous features of this alloy steel, including but without being limited to its corrosion-resistance, its high, pleasing luster, its surface hardness, the high degree of polish which it will take, and

the like. Among these articles, there may be cited as illustrative, desk ornaments, and ornamental bric-a-brac for the office and gravy boats, bowls, coasters, dishes, ladies, pitchers, pots, trays and the like for the home.

Thus, for the foregoing as well as for many other highly compelling reasons substantial effort has been directed in recent years by many manufacturers in this highly competitive field towards production of marketable stainless steel hollow-ware, as well as other sheet metal hollow-ware as having high sales appeal and substantial aesthetic value. While at first impression this appears to be a comparatively simple matter, experience proved this not to be the case. It was not enough simply to produce a utilitarian product subserving the desired functional requirement. To compete with generally similar articles of other metals already on the market, although they be semi-precious or even precious metals, substantial "eye-appeal" was found to be an essential requirement. The stainless steel and other comparatively inexpensive sheet metal products, over and above their superior qualities measured from a functional standpoint, and their low cost as compared to precious metals, must also achieve a high aesthetic level. In short, ornamentation had to be imparted placing those products on a comparable plane with similar products formed of the precious metals, as measured from an aesthetic standpoint.

It was right here, in imparting ornamentation to the stainless steel articles particularly, that unexpected difficulties were encountered. It was considered for various reasons that ornamentation, such as ornamental border strips and the like, had to be applied to the metal. Welding was found entirely unsatisfactory for this general purpose. Burning and distortion of the design on the strip made this entirely impractical. Hard solder had to be resorted to, employed in quantity. Here the excess solder had to be ground off and a final finish polish imparted to the completed article. Distortion in soldering frequently occurring, required further engraving, grinding and polishing. In the few instances where attractive results were achieved, substantial labor costs were found to be involved in assuring that the strip was maintained in proper position throughout the processing, as well as in the manufacturing technique itself. In short, the stainless steel border was by no means available or feasible from a practical standpoint. The product could not be applied by soldering or

welding at a reasonable price. The differential in price which contributed to the sales appeal of these articles as compared to those of precious metals diminished to the point where it was impractical to produce ornamental stainless steel hardware.

This, in short, was the problem which confronted me at the very outset—how to impart ornamentation to the stainless steel product which would be pleasing and effective in appearance, and at the same time would be sufficiently sure, certain and rapid as to involve low operational costs. An important object of my invention, therefore, may be conceived as the elimination and avoidance in substantial measure of the difficulties, deficiencies and drawbacks heretofore existing in the art, and at the same time to achieve the several objectives noted.

My invention may be envisaged as comprising the fabrication of stainless steel and various nickel, copper, brass, aluminum and like alloy sheet metal articles such as hollow-ware for table use by deep-drawing or stamping sheet or strip metal and then imparting a raised or repousse design to roughly formed articles at desired regions thereon. For this purpose I employ co-operating dies, preferably roller dies, one constituting a raised die, and the other a die having the corresponding depressed pattern thereon. In accordance with my invention the roughly formed vessel is passed between the dies, more especially the rim or edge is continuously fed between the dies, and the latter are applied thereagainst at a pressure which is determined nicely relative to the thickness of the metal, so that the latter will be caused to flow just sufficiently to take a sharp impression from the dies, without undue flow sufficient to occasion distortion or regions of physical weakness in the shaped article.

I find it entirely feasible to process all shapes of articles, oval, oblong, rectangular, circular, and the like, of three to thirty-six inches or more in greatest dimension, having thickness of 20 to 14 gauge. The precaution must be observed, however, that the edges of the pattern stamped or embossed in the metal must be at least one thirty-second of an inch from the nearest edge, corner or rim. If the pattern approaches more closely, a ragged design is imparted, with "run off" displayed, along with other indicia of inferiority. The dies, under such conditions, display a tendency to run off the surface of the metal.

Having more particular reference to the disclosure of Figures 1 and 2, sheet metal is deep-drawn into the rough form of a particular article, here typically illustrated as a vegetable dish 10. The pre-formed article is provided with a flat, outturned marginal rim 10A. While the article may be formed of any suitable stainless steel, copper, nickel, aluminum, silver, brass, Monel or like alloy sheet metal, I find the conventional 18-8 chromium-nickel steel (18% chromium, 8% nickel, with the remainder iron) to serve admirably for this purpose. Since it is produced in quantity, this grade is entirely satisfactory for such manufacture.

It is desired to provide a raised ornamental beading or design on the upper surface of rim 10A. This design I provide through the use of paired, cooperating dies, substantially rigidly mounted in parallel axes, that die with raised surface contours being placed lowermost and that with depressed configuration being disposed uppermost, the metal to be shaped and contoured

in accordance with the pattern of the die being placed therebetween.

I find it satisfactory to provide rotary dies, with a continuous die pattern imparted to the outer periphery thereof, and to feed the article 10 continuously and at uniform linear speed past or through the dies, by rotating the same about an axis which is at an angle to the axes of rotation of the dies. This I find to be far more rapid, simple, and easy of manipulation than stamping with reciprocating dies. Pattern overlap is encountered only at the end of the process. Development of skill on the part of the worker quickly suppresses and substantially eliminates this difficulty.

Accordingly, I provide an overlying circular rotary die element 11 fast on drive shaft 12 through its hub 13. On face 11a the female die pattern 11b is provided. Cooperating with the underlying roller 11 is a second, circular and rotary die element 15 fast on its drive shaft 14 through its hub 16 which drive shaft is substantially parallel to shaft 12. On face 15a of die 15 the male die pattern 15b is provided, which is complementary to and nicely fitted with respect to the female die pattern 11b. The linear rate of feed of rim 10a in rotating the work or article 10, the pressure between die elements 11 and 12, as well as the thickness of the sheet metal stock of which article 10 is formed, are all nicely correlated in empirical manner so that the metal is caused to flow sufficiently, and to take a good, sharp impression of required high definition.

While various thicknesses of sheet metal can be handled, I find my new method most suitable for thicknesses ranging between 14 and 20 gauges. Metal of a heavier gauge does not take the pattern satisfactorily and metal of a lighter gauge is inclined to distortion.

My new technique makes it possible for the first time to provide a pleasing, clear and undistorted ornamental beading, gadrooning or edging on stainless steel and other inexpensive sheet metal hollow-ware, and the like, and this in rapid, certain manner. As has been suggested, stainless steel hollow-ware, and generally similar articles thus ornamented, have pleasing appearance and substantial sales appeal, the price differential as compared with the cost of articles formed or precious or semi-precious metals such as silver adding appreciably to its marketability and attractiveness to the discriminating purchaser. The rapid continuous technique, requiring labor of only moderate skill, ensures that production costs are maintained low, without sacrifice, however, in quality of product. Stainless steels of conventional and commercial grades, and in commercial sizes, shapes and thicknesses, are admirably suited for this final processing step. All necessity of difficult finishing operations is eliminated in marked contrast to the necessities when applied beading is employed.

For the first time, really satisfactory ornamented metal products are made possible at reasonable price. Heretofore, competing products from the standpoint of initial cost such as steel plated with silver or other similar surfacing metals are found to rust and discolor in use. Corrosion is rapid, especially in moist as well as salty atmospheres. Articles such as table ware for marine and beach duty soon corrode. Articles of such nature as to be subjected to frequent handling as in the hotel and restaurant trade, likewise soon discolor with a scratching or wearing away of the plated surface. All of these

conditions of use are withheld by the ornamental articles of my invention.

It is apparent from the foregoing that once the broad aspects of my invention are disclosed, many embodiments thereof and many modes of application, all falling within the scope thereof, will readily occur to those skilled in the art. Moreover, many modifications of the embodiment and mode of execution herein disclosed will likewise suggest themselves. Accordingly, I intend to be limited only by the scope of the following claims, and I make the foregoing disclosure solely by way of illustration.

I claim:

1. In the fabrication of ornamented stainless steel hollow-ware, the art which comprises, shaping stainless steel sheet of 20-14 gauge to desired hollow-ware configuration with a free out-turned circumferential rim, and then continuously feeding said free out-turned rim by rotating said ware between male and female rotary dies operating in axes at an angle to the axis of rotation of said ware and cooperating at sufficient pressure and at sufficient distance from the edge of the rim to impart ornamentation thereto.

2. In the fabrication of ornamented sheet metal hollow-ware, the art which comprises, shaping sheet metal of 20-14 gauge to desired hollow-ware configuration with a free out-turned rim, and then continuously feeding said free out-turned rim by rotating said ware between a pair of power driven roller dies operating in axes at an angle to the axis of the rotation of said ware and cooperating at sufficient pressure and at a distance up to about $\frac{1}{8}$ inch from the edge of the rim to impart ornamentation to the rim.

ANGELO C. SCAVULLO.
